UNITED STATES PATENT OFFICE.

WALTER L. MAJORS, OF ST. LOUIS, MISSOURI, ASSIGNOR OF ONE-HALF TO ANNIE M. TURNBO, OF ST. LOUIS, MISSOURI.

HAIR-DRIER.

1,124,235.

Specification of Letters Patent.

Patented Jan. 5, 1915.

Application filed October 31, 1913. Serial No. 793,449.

To all whom it may concern:

Be it known that I, WALTER L. MAJORS, a citizen of the United States, residing at the city of St. Louis, State of Missouri, have 5 invented certain new and useful Improvements in Hair-Driers, of which the following is a specification.

This invention relates to hair drying apparatus, and the object of the present invention 10 resides in the provision of an improved apparatus of the character described, in which an air-heating device is employed in conjunction with an air fan and is located exterior of and so associated with the latter 15 that the cold air which discharges from the fan into the air tube has its temperature raised by the heated air which is drawn from the heating device into the air tube by the suction of the cold air entering the 20 latter.

Further, the present invention consists of the novel features of construction and arrangement of parts hereinafter more fully described and pointed out in the claim.

25 In the accompanying drawings forming part of this specification, in which like numbers of reference denote like parts wherever they occur, Figure 1 is a side elevation of a hair-drying apparatus embodying the 30 present invention, and Fig. 2 is a fragmentary vertical sectional view of the valve in the flue of the heating device.

In the present invention, an electric motor 1 of any suitable construction is preferably 35 employed, its casing being formed integrally with or otherwise secured to a fan casing or drum 2, and its shaft 3 extending into the interior of said casing or drum to drive the fan (not shown in the drawings) in the 40 usual manner. An air-inlet pipe 4 is secured to the cover 5 of the fan casing or drum 2 by a bolt 6 or a plurality of such bolts or other suitable means, and a discharge pipe 7 is connected with the air-outlet 8 of said fan 45 casing or drum. One end of the straight-way portion of a T 21 is preferably telescopically connected with the end of the discharge pipe 7 and the other end of said straight-way portion is connected with the 50 air-tube 22 by means of an ordinary union 23 or the like, which air-tube discharges the hot air upon the head of a person for the purpose of drying the hair of the latter, the branch 24 of said T being connected to the 55 upper end of a flue 25 by a union 26 or other

suitable means. The lower end of the flue 25 has an inverted funnel-shaped hood 27 secured thereto by a screw 28 or a plurality of such screws or other suitable means, said hood being adapted to receive the heat from either a gas or other kind of burner or heater 29 located beneath same. A plate 30, which is located within the lower part of the straight-way portion of the T 21, is soldered or otherwise secured along its side edges and 60 one of its end edges to the inner wall of the straight-way portion of said T, so that it slopes upwardly from the end of the straight-way portion that is connected to the end of the discharge pipe 7 and extends over 70 the branch 24, leaving a space 31 between the other end edge of said plate and the bottom of the straight-way portion for the hot-air to pass from the flue 25 into the air-tube 22. By this arrangement, the cool air which is 75 discharged from the fan passes through the pipe 7, then over the sloping plate 30 in the straight-way portion of the T 21, and into the air-tube 22, causing the hot air, which rises from the burner 29 into hood 27 and flue 80 25, to be drawn through the space 31 into the air-tube 22. In this way, the hot air from the burner 29 and the cool air from the fan become mixed within the air-tube 22, the result being the discharge of warm air from 85 said air-tube, which latter may be arranged to discharge the warm air upon the hair and head of a person for the purpose of drying same. The casing of the motor 1 may bear a lug 32 to be adjustably secured to a stand- 90 ard 33 by means of a thumb-nut 34, the latter fitting on a bolt 35 secured to the stand-ard 33 and said standard being preferably supported on and secured to a portable base 36. 95

It will be evident that by reason of locating the burner or heater 29 exterior of the fan casing 2 and, also, the discharge pipe 7 and introducing the hot air into the air-tube 22 by the suction of the cool air from the 100 fan as hereinabove described, the motor is prevented from becoming heated and burning out, as sometimes happens when a burner or heater is located either in the entrance to the fan casing, or in the exhaust pipe. 105

I claim:

In combination with a portable base having a vertical standard secured thereto, a casing having a motor driven fan therein, a lug depending from the casing and engag- 110

ing the upper end of the standard, a bolt passed through the upper end of the standard and through the lug, a nut on the bolt, a discharge pipe connected to the casing and 5 overlying said base, a T having one end connected to said discharge and having a second end projecting downwardly toward the base in spaced relation to the adjacent end of the casing, an air pipe connected to the 10 third end of the T, a funnel connected to

said second end of the T and overlying the base in spaced relation to the latter, and a heater on the base underlying the lower end of the funnel.

In testimony whereof I hereunto affix my ¹⁵ signature in the presence of two witnesses.

WALTER L. MAJORS.
